VACUUM TUBE OSCILLATOR

Richard E. Furay, San Francisco, Calif.

Application January 18, 1932, Serial No. 587,230
Renewed September 26, 1933

17 Claims. (Cl. 250—36)

This invention relates to vacuum tube oscillators, this application being a continuation in part of my copending application, Serial No. 508,687, filed January 14, 1931.

5 A primary object of this invention is to provide an oscillator having a high degree of frequency stability.

Other objects of the invention are: to provide an oscillator wherein the frequency-determining circuit is not called upon to supply current to the load circuit; to provide an oscillator wherein the frequency-determining circuit is substantially symmetrical; to provide a vacuum tube oscillator wherein the load imposed on the tube by the oscillating circuit is substantially constant throughout the cycle of oscillation; to provide a vacuum tube oscillator wherein the potential of the control elements is automatically varied to compensate for changes of anode potential; and, consequently, to provide an oscillator which is substantially unaffected in frequency by relatively large changes of supply current and potential.

Other objects of this invention will be apparent or will be specifically pointed out in the description forming a part of this specification, but I do not limit myself to the embodiment of the invention herein described, as various forms may be adopted within the scope of the claims.

Referring to the drawing:

30 Figure 1 is a vertical sectional view of the vacuum tube of my invention.

Figure 2 is a plan view of the tube elements, the plane of projection being indicated by the line 2—2 of Figure 1.

35 Figure 3 is a schematic circuit diagram of the oscillating circuit of my invention, embodying the tube shown in the first two figures.

Figure 4 shows the characteristic curves of the tube, indicating the operating range thereof when 40 used in the circuit of Figure 3.

My invention comprises an oscillator embodying in a vacuum tube having a plurality of control elements which may be operated so that changes in the potential thereof have opposite effects upon 45 the plate current, i. e., wherein the negative swing of potential of one of the control elements increases the output current, while a similar swing of the other element decreases the output current. The two control elements are connected by a parallel-tuned circuit, which is coupled to the plate of the oscillator tube. The frequency of oscillation is determined almost wholly by the tuning of the parallel circuit connecting the two control elements. The tube preferably used comprises 50 the usual filament, plate, and grid-control ele-

ment mounted between filament and plate, and an additional control element, which I have termed a "reflector", positioned on the opposite side of the filament from the plate. When operated at a proper positive potential the two control elements have opposite effects on the plate current, as above stated. This positive potential is preferably derived from the plate circuit through a resistor. With this arrangement the control-element potential is a function of the plate potential, varying with it in such a manner that variations in plate current or voltage are almost completely compensated and a high degree of frequency stability is secured even though the supply sources feeding the tube may vary. 15

A preferred form of my device utilizes a tube having the usual envelope 1 having a stem 2 upon which the elements of the tube are mounted. Sealed through the stem are a pair of filament leads 3, 4, a plate support and lead 5, and a grid support and lead 6. The stem also carries a plurality of supports or "dummies" 7, 9, 10 and 11, to which are attached the various elements of the tube as will be described.

The supports 6, 7, 9 and 11 extend toward the top of the tube to above the elements, and secured to their upper ends are a pair of insulating bars 12, preferably of glass, which tie the supports together to form a rigid structure, and to each of these bars is secured a spring hook 14. 30

The filamentary cathode 15 of the tube is mounted substantially in a plane, and extends from the lead 3 up over one of the hooks 14, thence toward the stem 2 where it is hooked over a dummy 16 mounted in the stem, thence up and 35 over the second hook 14 and back to the lead 4.

The plate 17 is positioned substantially parallel to the filament and is mounted on the lead 5 and dummy or support 10, the top of the plate being steadied by the short wires 19 which are 40 sealed into the insulating bars 12.

A planar grid 20 is positioned between the cathode and the plate, and comprises parallel wires extending between supports 6 and 9. This grid acts in the manner familiar in the ordinary triode 45 construction, and can take almost any of the many forms which have been developed for this purpose.

Positioned on the opposite side of the filament from the grid is the control plate or reflector 21, 50 which is secured to the wires 7 and 11. The lead to this element, in the form of the device here shown, is a wire 22 which is sealed through the tip 24 of the tube.

The two control elements 20 and 21 are sym- 55

metrically placed with respect to the plate, and hence have different effects upon the plate current as is shown by the curves of Figure 4. The curve 25 illustrates the effect of varying the potential of the grid 20 with the reflector maintained at zero potential. Curve 26 shows the effect on the plate current of varying reflector potentials with the grid maintained at zero. With different potentials on either control a family of curves may be drawn for the other control element, each curve of the family being substantially parallel to the others and having maxima and minima at substantially the same control voltages, although these maxima and minima are of different values for the different curves.

It will be seen that for relatively low control voltages the effect of the two control elements is in the same direction, i. e., for voltages less than those indicated by the dotted line *a* the plate current increases with increasing potential. At the control voltage *a* and above, increasing the potential of the reflector decreases the plate current, whereas increasing the grid potential increases the plate current. At a much higher positive potential the effect of increasing the grid potential also reverses, in the range higher than that indicated by the dotted line *b* of the graph. The operating range of this device is between the control voltages indicated by the lines *a* and *b*.

30 The tube is preferably operated in a circuit whose preferred form is shown in Figure 3. The filament 15 is heated by a suitable source 30. The grid 20 and reflector 21 are connected at opposite ends of a parallel-tuned circuit comprising an inductance coil 31 and variable condenser 32. The plate 17 is connected through a second parallel-tuned circuit, comprising an inductance 34 and variable condenser 35, to a suitable plate supply 36 and thence back to the filament. The 40 two parallel-tuned circuits are coupled, preferably by means of a high resistance 37 shunted by a by-pass condenser 39, this coupling circuit being preferably connected to the two inductances by variable taps 40 and 41 respectively.

45 Since both of the control elements are operated at positive potential, each of these elements will draw current. This current, flowing through the resistor 37, causes a potential drop, so that the control elements operate at a potential lower than the plate but which is a definite function of the plate potential. The magnitude of this resistor and the potential drop will, of course, vary with the size of the tube and with the plate potential, but the correct size for this resistor may readily 50 be deduced from the operating characteristics of the particular tube, the resistor being so chosen as to bring the mean operating potential of the two control elements midway between the control potentials *a* and *b* of Figure 4.

60 The positive control element potential also has the effect of reducing the output impedance of the tube to a much lower value than would obtain with a tube of comparable dimensions operated at a negative bias. This leads to high plate 65 circuit efficiency, and, since the mean control potential is substantially constant, does not introduce wave form distortions which are objectionable.

70 Since the filament, which may be considered as ground potential, operates midway between the grid and the reflector, there will be a node of potential approximately midway between the ends of the coil 31. The adjustable tap 41 is displaced slightly from this potential node. The 75 coupling of the two oscillating circuits is deter-

mined by the position of both of the taps 40 and 41, these taps being preferably positioned to give the minimum coupling at which stable operation occurs.

In the operation of the device the frequency 5 is determined almost entirely by the tuning of the parallel "tank" circuit comprising the inductor 31 and condenser 32, it being possible to vary the tuning of the plate circuit through wide limits without material frequency variations. 10 The effect of the plate circuit tuning does, of course, vary the intensity of the oscillation and the energy output, but until this circuit is thrown so far out of tune that the coupling back to the control tank circuit is almost entirely out of 15 phase, oscillation will still take place with a frequency variation of substantially nil.

The control element circuit is, in fact, almost self-oscillatory. The current drawn from this circuit is only that to the control elements of 20 the tube, however, and since these elements are varying in opposite directions at the same time this load is substantially a constant regardless of the oscillating power withdrawn from the plate circuit of the device. This fact is, of itself, sufficient to account for the remarkable frequency 25 stability of the circuit, and the supply of the positive grid potential as a function of the plate voltage is a factor which increases this stability.

In practice the device has been found to work 30 over long periods of time and with widely varying plate voltages without perceptible drift in frequency. Since changes in frequency with temperature are largely due to thermal effects upon voltage and current, the device also shows remarkable 35 temperature stability.

Another factor which increases the frequency 40 stability of the tube is the fact that changes in the plate circuit impedance vary the effective capacity of the two control electrodes in opposite 45 directions, so that the net input capacity of the tube varies little with changing load.

Those familiar with modern vacuum tube practice will at once recognize that various modifications in the method of coupling the tuned circuits 50 and in applying the positive of bias to the control element are possible without affecting the operation of this device. I therefore do not desire to be limited by the exact form shown, but wish to protect the invention as defined in the following 55 claims.
